CLAIM

The ornamental design for a suspended active display, as shown and described.

DESCRIPTION

FIG. 1 is a perspective view of suspended active display showing my new design;

FIG. 2 is a front elevational view thereof; the other two faces being a mirror image of the view of FIG. 2 with differing orientations of the supporting line;

FIG. 3 is a top plan view thereof; and,

FIG. 4 is a bottom plan view of our suspended active display.
